UNITED STATES PATENT OFFICE.

CHARLES L. CAMPBELL AND MORRIS T. MARTIN, OF CHICAGO, ILLINOIS.

MACHINE FOR MANIPULATING CARDS OR TICKETS FOR CREATING VALUE.

SPECIFICATION forming part of Letters Patent No. 290,395, dated December 18, 1883.

Application filed August 8, 1883. (No model.)

To all whom it may concern:

Be it known that we, CHARLES L. CAMPBELL and MORRIS T. MARTIN, both of Chicago, in the county of Cook and State of Illinois, 5 have invented certain new and useful Improvements in Machines for Manipulating Cards or Tickets for Creating Value; and we do hereby declare that the following is a full, clear, and exact description of the invention, which will 10 enable others skilled in the art to which it appertains to make and use the same, reference being had to the accompanying drawings, and to letters of reference marked thereon, which form a part of this specification.

15 The object of our invention is to provide a machine which, by the manipulation of a number of tickets, creates a fictitious market or value. This we accomplish by a machine having a box divided into two ticket-receptacles, 20 in the upper of which are placed a number of tickets. The outer visible ticket in the upper receptacle is then pushed downward through a suitable slot into the lower receptacle by a vertically-reciprocating plate, which, 25 when withdrawn, leaves visible through openings in the frame behind which said box is placed two tickets, one in the upper, representing profit to the buyer, and one in the lower, representing profit to the seller. These 30 surface tickets are then pushed laterally out of their respective receptacles by a horizontally-reciprocating plate, which closes the openings through which said tickets are seen, while the next following surface card in said 35 upper receptacle is pushed into the lower, after which it is removed. This operation is repeated until the package of tickets in the upper receptacle is exhausted.

In the drawings, Figure 1 is a front elevation, Fig. 2 is a rear elevation, Fig. 3 is a 40 vertical longitudinal section, and Fig. 4 is a horizontal transverse section, of our invention.

In the drawings, A represents a rectangular 45 box-shaped frame, open at the back, and provided in front with a rectangular opening, B, of a length a little less than twice that of the tickets used in connection with our machine, and of a width a little less than the width of 50 the same, said openings being divided into an upper and lower opening by a cross-bar, b.

Placed immediately back of and having its

open side facing and opening into the opening B is a box, C, which is divided into two compartments or card-receptacles, D and E, by a 55 partition, c. In each of these compartments is arranged a plate, d, and spring e, pressing outward against the plate toward the opening B.

In that part of the top of the box C contiguous to the frame A, just above the opening B, is a slot, g, and in the partition c, just behind the cross-bar b, there is a similar slot, g'.

Arranged immediately above the box C, so as to reciprocate vertically in the guides f 65 down through the slot g, so as to push the upper surface card into the lower receptacle, is the plate F, which is operated by a lever, G, pivoted thereto at one end, fulcrumed at or near its center of length, and provided with a 70 handle at its other end, which passes through the side of the frame A, by which it is manipulated. The sides of the box C contiguous to the frame A and parallel with the sides of the opening B are also provided with a slot, h, extending from top to bottom of said box. Placed, say, to the left of this box C, and moving in the guides i, is the horizontally-reciprocating plate H. This plate moves through the contiguous slot h to push the surface tickets from both upper and lower receptacle, and closes the open side of the box C while the next following surface card in the upper receptacle is being pushed down into the lower. This plate is operated by a lever, k, arranged 75 vertically, pivoted at its upper end thereto, fulcrumed at or near its center of length, and provided with a handle at its lower end, by which it is manipulated. As the tickets are pushed out of the card-receptacles through the 80 slot h in the side of the plate farthest from the plate H, they are toppled over by a spring-cam, m, nearly on a plane with the tops of the tickets, and, falling, they are caught on a suitable platform, I, one end of which is vertical, so as to prevent the cards from slipping off thereof.

We do not deem it a departure from the principle of our invention if the plate F and contingent mechanism are dispensed with; but in 100 such a case two packs of cards are used, one in either card-receptacle, the surface tickets being pushed out with one and the same stroke.

What we claim as new, and desire to secure by Letters Patent, is—

1. The card-box C, having an upper and lower receptacle, in each of which are spring-actuated plates, said box being provided with vertical slots, as set forth, whereby the surface ticket in the upper receptacle can be pushed by suitable means into the lower one, and thence out of said box.
2. The combination, with the box C, having receptacles D and E, each of which are provided with means for pushing the tickets therein outward, and having slots h, of the horizontally-reciprocating plate H, and means for operating the same.
3. The combination, with the box C, divided into an upper and lower compartment, in each of which are spring-actuated plates, said

box having therein the slots g and g', of the plate F, and means for operating the same.

4. The combination, with the box C, having vertical and transverse slots, and divided into an upper and lower ticket-receptacle, in each of which are suitable means for pushing said tickets outward from the open side of said box, of the plates F and H, and means for operating the same.

In testimony that we claim the foregoing as our own we hereunto affix our signatures in the presence of two witnesses.

CHARLES L. CAMPBELL,
MORRIS T. MARTIN.
